UNITED STATES PATENT OFFICE.

EDWARD KAYLOR, OF ALLEGHENY, PENNSYLVANIA.

CAR-TRUCK SIDE FRAME.

No. 833,719.

Specification of Letters Patent.

Patented Oct. 16, 1906.

Application filed February 16, 1905. Serial No. 245,853.

To all whom it may concern:

Be it known that I, EDWARD KAYLOR, of Allegheny, Allegheny county, Pennsylvania, have invented a new and useful Car-Truck 5 Side Frame, of which the following is a full, clear, and exact description, reference being had to the accompanying drawings, forming part of this specification, in which—

Figure 1 is a perspective view showing one 10 form of my improved side frame with the spring-blank connection. Fig. 2 is a partial top plan view on a larger scale; and Fig. 3 is a plan view of the blank, showing the method of bending. Fig. 4 is a top plan view showing a modified form. Fig. 5 is a longitudinal 15 section of the truck of Fig. 4, and Fig. 6 is a similar view showing another form.

My invention relates to side frames for car-trucks, and is designed to provide a frame 20 which may be easily and cheaply made and will be strong and efficient.

In the drawings, referring to Figs. 1, 2, and 25 3, I show the frame proper as made from the blank 2, which is cut in the form shown in Fig. 2 and is then bent along the dotted lines of this figure, so as to form flanges 3 and 4 at the ends and flanges 5 and 6 along the edges of the intermediate body portion. This body portion may be cut out, as shown in Fig. 2, 30 and the cut-out portions may be flanged or not, as desired. In this form 7 represents the spring-blank, and 8 the guide-columns, which may be secured by through-bolts and extend between the flanges 5 and 6. The 35 side frame is strengthened by the longitudinal plate or bar 9, which is bent to conform to the lower flanges 4 and 6 and preferably fills the space between the flanges 3 and 4. These parts may be riveted or secured to- 40 gether in any desirable manner. In this form the strengthened member 9 is continuous throughout the length of the side frame.

In the form of Figs. 4 and 5 the construction is similar to that of the first figures except that the strengthening members 9' are 45 separated and extend through only a portion of the flange 6'. In this case the side frames are connected by the transom-channels 10 10, which may be secured to the side frames 50 in any desirable manner, preferably by riveting the channel-flanges to the flanges 5' and 6', as shown at 11, and also by riveting the bent bracket portions 12 to the webs of the channels. These bracket portions 12 are 55 preferably cut and bent inwardly from the plate forming the side frame, and strengthen-

ing-ribs or swelled portions 13 are preferably provided in these brackets.

In the form of Fig. 6 the strengthening member 9^a is continuous, the web of the 60 plate 2 is left solid, and bent transom members 10^a are employed.

The advantages of my invention result from forming the side-frame body from one plate, which is bent to form the top and bottom flanges throughout the body and pedestal portions, also from the use of the strengthening member, which preferably fills the space between the pedestal-flanges, and from the strength and simplicity of the structure. 70 The frame is light, easy to form, and by having the flanged openings makes access easy to the brake hangers, shoes, springs, and other parts of the truck. Being made of a single sheet, the parts of the truck are few and not 75 liable to get out of order.

The strengthening bars or plates following the contour of the lower flange or arch-bar for a part or all of its length are for the double purpose of strengthening the side frame and 80 forming filler-blocks between the flanges or arch-bars at the ends of the side frame.

The top and bottom flanges or arch-bars of the side frame being joined by a web of metal, the tensile strength of said web is 85 gained toward carrying the load.

The strengthening member may extend in and be secured to the transom or spring-plank, and many variations may be made in the form and arrangement of the side frame 90 and the other portions of the truck without departing from my invention.

I claim—

1. A truck side frame formed of a plate 95 cut to the desired shape with integral bent top and bottom flanges, and longitudinal strengthening members secured between the pedestal-flanges; substantially as described.

2. A truck side frame formed of a single plate with bent flanges extending along the 100 top and bottom of the web and parallel pedestal-flanges, and strengthening members filling the space between the pedestal-flanges and extending along the bottom flange of the body; substantially as described.

3. A truck side frame formed of a single plate of metal, with bent top and bottom flanges whose end portions are substantially 110 parallel, and a single strengthening member extending along the lower flange and lying between the parallel end flanges; substantially as described.

4. A side frame for a car-truck of the diamond type having top and bottom arch-bar members formed from a single sheet of metal and connected by the intervening integral portion of the sheet; substantially as described.

5. A side frame for a car-truck of the diamond type having top and bottom arch-bars shaped from a single sheet of metal, the intermediate portion of the sheet having openings cut and flanged therein; substantially as described.

6. A side frame for a car-truck formed from a single sheet of metal and a reinforcing bar or plate extending from end to end and following the contour of the lower flange or bar; substantially as described.

In testimony whereof I have hereunto set my hand.

EDWARD KAYLOR.
